UNITED STATES PATENT OFFICE.

PETTER CARLSSON KJELLBERG, OF STOCKHOLM, SWEDEN.

MACHINE FOR PACKING MATCHES IN BOXES, &c.

SPECIFICATION forming part of Letters Patent No. 593,944, dated November 16, 1897.

Application filed February 26, 1895. Serial No. 539,814. (No model.) Patented in Sweden May 12, 1894, No. 5,434.

To all whom it may concern:

Be it known that I, PETTER CARLSSON KJELLBERG, a subject of the King of Sweden and Norway, and a resident of Stockholm, Sweden, have invented certain new and useful Improvements in Machines for Packing Matches in Boxes, Paper Cases, or the Like, (for which I have obtained a patent in Sweden, No. 5,434, bearing date May 12, 1894,) of which the following is a specification.

This invention relates to improvements in such machines for packing matches in boxes, paper cases, or the like of the kind wherein the matches are brought down in a horizontal position in a number of compartments arranged side by side in order to be measured off in determinate quantities for packing by means of slides which are pushed in between the matches in the said compartment and the store of matches above them.

Figure 1 on the annexed drawings represents the machine in side elevation and section on the lines a^x in Fig. 2 and b^x in Fig. 3. Fig. 2 represents the machine from the end in section on the lines c^x in Fig. 1 and d^x in Fig. 3. Fig. 3 represents the machine in plan section on the lines e^x e^x in Figs. 1 and 2. Figs. 4, 5, and 6 show the essential parts of the machine on a larger scale. In Fig. 4 the part of the machine is shown from the side in section on the lines f^x in Fig. 5 and g^x in Fig. 6. Fig. 5 is an end view of said part in section on the lines h^x h^x in Figs. 4 and 6. Fig. 6 is a plan section on the lines i^x i^x in Figs. 4 and 5.

a is the magazine in which the store of matches is placed; b , the matches; c , the partition-walls between the compartments d , in which compartments the matches to be measured off are brought down.

e are the slides, which are movable in the longitudinal direction of the matches and by means of which the measuring off of the matches is effected.

e' is a cross-head to which the slides e are attached; e^2 , the link connecting the cross-head e' with the lever e^3 , pivoted at e^4 , and engaging in the cam-groove e^4 in the disk e^5 , which cam-groove operates the movements to and fro of the slides e among the matches.

e^5 is fixed on the main shaft l of the machine.

f are grooves both in the insides of the side

walls of the magazine a and in the sides of the partition-walls c . The slides e have narrowed end extensions disposed and movable longitudinally of the matches. Two slides e are placed in each compartment d , and the side edges of the slides e move in the grooves f when the slides pass to and fro among the matches, thus preventing the aforesaid points from striking against the ends of the matches in the compartments d , which matches otherwise probably would be split.

g are movable implements which are arranged horizontally in the narrow spaces between the adjacent edges of the slides e and are intended to push away such matches as happen to come in the way of the slides e when they are pushed in among the matches, thereby preventing said matches from being split or otherwise damaged by said slides. To effect the pushing away of the matches in question, said implements g are during the measuring off of the matches moved quickly up and down, which movement may of course be accomplished in many different ways. For instance, a horizontal bar h , provided with teeth on the upper side, is moved forward and backward across the compartments beneath the part of the implements g which is outside the compartments d . These implements are quickly lifted by the elevated parts of the bar h , acting on the tooth g^3 on the frame g' , which frame oscillates around the journal g^2 and carries all the implements g , and when moved upward is immediately afterward pressed down in the hollows between the teeth of the bar h by the spring g^4 . Said movement to and fro of the bar h is derived from a cam-groove h^4 in a drum on the main shaft l by means of the rods h^1 , h^2 , and h^3 , the toothed bar h being attached to the rod h^1 .

i are the pistons which push the matches that are separated in the compartments d out from the said compartments. These pistons i are attached to the cross-piece i' , that is connected with the lever i^3 by means of the link i^2 . The lever i^3 is pivoted at i^5 . The movement of the pistons i is derived from a cam-groove i^4 in the disk e^5 , in which the lever i^3 engages.

k are the vertical sliding doors that leave passage for the matches that have been measured off and are to be pushed out from the

compartments *d* for the packing in the boxes. These doors are worked as follows: At the end of the forward movement of the lever *e*³ the inclined surface *k*³ on a prolongation of 5 said lever *e*³ acts upward on the pin *k*⁴ of the bar *k*² and the bar *k*² is raised. Said bar *k*² carries pins *k*', that are affixed to doors *k* and pass through slots *k*⁵ in the outer wall of the magazine *a*, and the doors *k* are lifted at the 10 same time as the bar *k*². The doors are moved downward or shut, when the lever *e*³ is returning, by means of the inclined surface *k*⁵, which acts upon the pin *k*⁴ just as the surface *k*³, but in the opposite direction. 15 The implements *g* in the arrangement shown are placed horizontally; but they may obviously occupy a vertical position.

I claim as my invention—

1. In machines for packing matches in 20 boxes, paper cases and the like, the combination of a reservoir for the matches and com-

partments *d* adapted to hold the matches horizontally, with slides *e* provided with narrowed end extensions lying longitudinally in, and movable in the longitudinal direction of, 25 the matches in said compartments, and means for moving said slides, substantially as and for the purpose set forth.

2. In machines for packing matches in boxes, paper cases or the like, the combination of the compartments *d* provided with grooves *f*, with the slides *e* provided with a pointed side edge, and the vibrating implements *g*, substantially as and for the purpose set forth. 30

In testimony whereof I have signed my name to this specification in the presence of two subscribing witnesses.

PETTER CARLSSON KJELLBERG.
